SAFETY WARNING SIGN FOR STAIRS

Otto A. Hendrickson, Conover, Wis.

Application June 10, 1949, Serial No. 3,172

Term of patent 7 years

(CL. D72—1)

To all whom it may concern:

Be it known that I, Otto A. Hendrickson, a citizen of the United States, residing at Conover, in the county of Vilas and State of Wisconsin, have invented a new, original, and ornamental Design for a Safety Warning Sign for Stairs, of which the following is a specification, reference being had to the accompanying drawing, forming a part hereof.

In the drawing:

Figure 1 is a plan view of a safety warning sign for stairs showing my new design, and

Figure 2 is a cross sectional view thereof taken substantially along a plane as indicated by the line 2—2 of Figure 1.

I claim:

The ornamental design for a safety warning sign for stairs, as shown.

OTTO A. HENDRICKSON.
